UNITED STATES PATENT OFFICE.

JOHN F. O'CONNOR, OF CHICAGO, ILLINOIS, ASSIGNEE TO WILLIAM H. MINER, OF CHICAGO, ILLINOIS.

MEANS FOR CONNECTING THE DRAFT-YOKE TO THE DRAW-BAR IN RAILWAY-CARS.

1,160,642.

Specification of Letters Patent. Patented Nov. 16, 1915.

Application filed July 31, 1912. Serial No. 712,525.

To all whom it may concern:

Be it known that I, JOHN F. O'CONNOR, a citizen of the United States, residing at Chicago, in the county of Cook and State 5 of Illinois, have invented a certain new and useful Improvement in Means for Connecting the Draft-Yoke to the Draw-Bar in Railway-Cars, of which the following is a full, clear, concise, and exact description, 10 reference being had to the accompanying drawings, forming a part of this specification.

My invention relates to improvements in means for connecting the draft yoke to the 15 draw bar in railway cars.

The object of my invention is to provide a safe draw bar and yoke connection, and one permitting the convenient disconnection of draw bar and yoke when desired.

20 In the accompanying drawings forming a part of this specification Figure 1 is a plan view partly in longitudinal section of a draw bar and yoke connection embodying my invention. Fig. 2 is a side elevation 25 partly in vertical longitudinal section. Fig. 3 is a cross sectional view on line 3—3 of Fig. 2. Figs. 4, 5 and 6 illustrate a modification; Fig. 4 being a plan view partly in longitudinal section, Fig. 5 a side elevation partly in vertical longitudinal section, and Fig. 6 a cross sectional view on line 6—6 of Fig. 5.

In the drawings 7 represents a draft yoke, and 8 and 9 the upper and lower limbs 35 thereof respectively, which are provided near their forward ends with the vertical slots 10, 10. The draw bar 11, (partly shown in drawings), is provided through its butt 12 with the vertical slot 13. The front 40 follower 14 disposed between the upper and lower limbs of the yoke 7 is provided with a hollow head or hood 15 having the longitudinally extended vertical perforations 16, 16. The limbs 8 and 9 of yoke 7 extend at 45 their forward ends within hollow head 15 and engage the butt 12 of the draw bar between them. The perforations 16, 16 in the hollow head 15 in the draw bar and 10, 10 in the limbs of the yoke register to receive 50 the vertical, preferably flat key 17, which is secured in place by the pin 18 passed through the key and the longitudinally extended transverse slots 19, 19 provided in the boss 20 with which the lower outer sur-

face of the head 15 is furnished. The head 55 15 is provided on its interior with the shoulder 21 with which the rear face 22 of the draw bar contacts in its rearward movements, the key being relieved of severe buffing strains. On forward movement of draw 60 bar the front follower engages the usual stop members, and while the front follower 14 and its head 15 remain stationary the yoke 7 moves forwardly with the draw bar, the key 17 sliding in the longitudinal slots 65 16, 16 of the hollow head 15.

From the preceding description, it will be seen that the head or hood 15 is movable relatively to the yoke or casing 7 or, as it is sometimes termed, the head or hood is movable axially of the yoke.

In the modification illustrated in Figs. 4, 5 and 6, 23 represents the draft yoke, and 24 and 25 its upper and lower limbs respectively, 26 the draw bar provided with 75 the vertical slot 27, 28 the front follower, and 29 a hollow head adapted to receive the butt of the draw bar. As shown, said head or hood 29 is separate from the follower 28 and is also provided with longitudinally extending slots 30—30' within which are slidably received the limbs of the draft yoke. The key 31 passes through the alined vertical openings 27, 32, 32 and 33, 33 in the draw bar, limbs of the draft yoke and hollow head, respectively. The openings 33 in the head are longitudinally extended to permit the key 31 to slide therein, and on rearward movement of the draw bar its rear face 34 engages the shoulder 35 provided 90 within the opening of the hollow head 29.

I claim:

1. In a device of the character described, a means of connecting the draw bar and draft yoke, said means consisting of a hollow head slidably connected with both the yoke and the draw bar.

2. In a device of the character described, a means of connecting the draw bar and draft yoke, said means consisting of a follower provided with a hollow head and a key, said key engaging the yoke and the draw bar, and being slidably connected with said hollow head.

3. In a device of the character described, a means of connecting the draw bar and draft yoke, said means consisting of a follower provided with a hollow slotted head and a

key passing through the draw bar and said head, and slidably engaging within the slots of said head.

4. In a device of the character described, 5 the combination with the draw bar, draft yoke and key, of a front follower provided with a hollow head to receive the draw bar and the draft yoke, the head, draw bar and yoke being slotted to receive the key, and the 10 said key being in sliding engagement with the follower's head.

5. In a device of the character described, 15 a means of connecting the draw bar and draft yoke consisting of a follower provided with a hollow head slidably connected with the draw bar and yoke, and provided with an internal shoulder engaging the draw bar in its buffing movement.

6. In a device of the character described, 20 in combination, a follower, a draw bar, a draft yoke and a key, the key passing through the draw bar follower and yoke, the follower being in sliding engagement with said key.

25 7. In a device of the character described, in combination, a follower having a forwardly extended hood, a draft yoke and draw bar within the hood, and a key connecting the draft yoke to the draw bar, the 30 said key being adapted to force the follower rearwardly on rearward movement of the draw bar, and to slide within said hood on forward movement of the draw bar.

8. In a device of the character described, 35 in combination, a draw bar, a yoke connected thereto, a follower in sliding engagement with the draw bar and yoke, the said yoke having extensions adapted to force the follower rearwardly on rearward movement of the 40 draw bar, and to slide within the same on forward movement of the draw bar.

9. In a draft rigging, the combination with a draft gear casing, of a hood mounted

on the forward end of the casing to move axially of the casing.

45 10. In a draft rigging for cars, a casing for a draft gear, a hood mounted on the front end of said casing and provided with elongated key-ways through its walls, a draw-bar the rear end of which is positioned 50 in said hood, a key-way through the rear end of said bar, and a key of width less than the length of said elongated key-ways of the hood.

55 11. In a draft rigging for cars, the combination with a yoke, of a hood located on the forward end of the yoke and provided with elongated key-ways, a draw-bar the rear end of which is mounted in said hood, 60 said hood being separable from the draw-bar and yoke and inclosing the ends of the yoke and a key passing through said elongated key-ways and through the arms of the yoke and rear end of the draw-bar.

65 12. In a device of the character described, a yoke, a hollow head, confining the ends of the yoke, a draw-bar, and means for connecting said yoke and draw-bar to move the same in unison in both buff and draft and for holding the head in its confining relation to the yoke, said yoke and draw-bar being movable independently of the head under draft.

70 13. In a device of the character described, a tandem yoke having an intermediate thimble, a draw-bar, a hood within which the front ends of said yoke arms are received, and means for connecting the parts, said means being so arranged that the yoke and draw-bar are movable in unison in both buff 80 and draft and the hood is movable with the draw-bar under buff only.

JOHN F. O'CONNOR.
